VENTILATING WINDOW ASSEMBLY AND LATCH THEREFOR

Guy M. Lane and Harold G. Thunder, Detroit,
Mich., assignors to Motor Products Corporation,
Detroit, Mich., a corporation of New York

Application September 8, 1947, Serial No. 772,743

4 Claims. (Cl. 296—44)

1

This invention relates generally to window assemblies and refers more particularly to improvements in ventilator windows of the type employed on vehicle bodies.

Ventilator windows of the type to which the present invention pertains usually comprise a main frame and a ventilator supported in the frame for swinging movement about a generally vertically extending axis located between the front and rear edges of the ventilator.

It is customary in most ventilator window designs to provide some means at the inner side of the ventilator for latching the same in its closed position with respect to the main frame. This is ordinarily accomplished by a latch arm pivotally supported on the bottom bar of the ventilator frame in a position rearwardly of the axis of swinging movement of the frame.

Regardless of the particular location of the latch arm on the ventilator window, it is nevertheless readily visible by occupants of the vehicle, and it is, therefore, one of the objects of this invention to provide a latch assembly which imparts a pleasing appearance to the ventilator window.

Another object of this invention is to provide a latch assembly composed of a relatively few number of parts capable of being inexpensively manufactured, assembled and installed.

The foregoing as well as other objects will be made more apparent as this description proceeds, especially when considered in connection with the accompanying drawing, wherein:

Figure 1 is a fragmentary elevational view of a ventilator window embodying a latch assembly in construction in accordance with this invention;

Figure 2 is a sectional view taken on the line 2—2 of Figure 1; and

Figure 3 is a sectional view taken on the line 3—3 of Figure 2.

Referring now more in detail to the drawing, it will be noted that the reference numeral 10 indicates a part of a vehicle body ventilator window comprising a main frame 11 and a ventilator 12. The ventilator 12 is supported in the main frame 11 for swinging movement about a generally vertically extending axis 13 located between the front and rear edges of the ventilator. As is customary in ventilator windows of the above type, the main frame is constructed to support a flexible weather strip 14 shaped to establish a weather-tight seal between the ventilator 12 and main frame when the former is in its closed position.

The ventilator 12 comprises a glass panel 14 and a frame 15. In accordance with convention

2

practice, the frame 15 is formed of top, front and bottom bars substantially channel-shaped in cross section for receiving the adjacent marginal edge portions of the glass panel 14. The front bar of the ventilator frame is pivotally connected intermediate the ends thereof to the adjacent bar of the main frame by a pivot assembly 16 having its axis coincident with the axis 13. The bottom bar 17 of the ventilator frame is also pivoted to the bottom bar of the main frame by a pivot assembly 18 having its axis also coincident with the axis 13. The pivot assemblies form no part of the present invention, and are therefore, not described in detail herein. It will suffice to point out that these pivot assemblies are of a nature to permit swinging movement of the ventilator 12 about the vertical axis 13.

The ventilator is secured in its closed position with respect to the main frame by means of a latch assembly 19 comprising a cam plate or keeper 20 and a latch arm 21. The keeper 20 is secured to the bottom bar of the main frame 11 rearwardly of the axis 13, and is provided with an inwardly extending cam portion 22 for engagement with the latch arm 21 in a manner to be more fully hereinafter set forth.

The latch arm 21 is carried by a bracket 23 having an upstanding part 24 occupying a position in a slot 25 formed in the inner flange of the channel-shaped bottom bar 17 and forming a pivotal support for the latch arm 21. An attaching flange 26 extends laterally outwardly from the lower end of the upstanding part 24 into the channel of the bottom bar 17 below the adjacent edge of the panel 14, and is secured to the base of the channel bar 17 by rivets 27. The attaching flange has a length greater than the length of the slot 25 to assure a rigid connection between the bracket 24 and the bar 17. The upstanding part 24 has a length corresponding approximately to the length of the slot 25, so as to substantially close the latter and an escutcheon plate 28 is secured to the inner surface of the part 24 to conceal the latter and slot 25. The plate 28 is, of course, centrally apertured to receive the hub of the latch arm 21, and is formed with an outwardly extending flange 29 at the upper end which overlies the top of the slot 25 in the bottom bar 17. Thus it will be noted that the construction presents a neat and pleasing appearance from the inner side of the window.

The latch arm 21 is shown in Figure 1 of the drawing as having an operating handle 30 and a projection 31 positioned to engage the keeper 20 or cam plate 22 when the arm 21 is swung to its

latched position to secure the ventilator in its closed position in the window frame 11.

What we claim as our invention is:

1. A ventilator window assembly comprising a main frame, a ventilator panel supported in the main frame for swinging movement about a generally vertically extending axis, a frame for the ventilator panel having an upwardly opening channel-shaped bottom bar for receiving the lower edge portion of the panel and having a slot in the inner flange of said bar spaced to one side of the axis of swinging movement of the ventilator panel, a bracket having a part occupying a position in said slot and having a portion secured to the base of the channel-shaped bottom bar, a latch arm pivoted to said part and means on the main frame engageable with the arm in one position thereof to secure the ventilator in its closed position.

2. A ventilator window assembly comprising a main frame, a ventilator panel supported in the main frame for swinging movement about a generally vertically extending axis, a frame for the ventilator panel having an upwardly opening channel-shaped bottom bar for receiving the lower edge portion of the panel and having a slot in the inner flange of said bar spaced to one side of the axis of swinging movement of the ventilator panel, a bracket having a part occupying a position in said slot and having a portion secured to the base of the channel-shaped bottom bar, a latch arm pivoted to said part and engageable with means on the main frame for securing the ventilator in its closed position in the main frame, and an escutcheon plate concealing said part and slot.

3. A ventilator window assembly comprising a main frame, a ventilator panel supported in the main frame for swinging movement about a generally vertically extending axis, a frame for the

ventilator panel having an upwardly opening channel-shaped bottom bar for receiving the lower edge portion of the panel and having a slot in the inner flange of said bar spaced to one side of the axis of swinging movement of the ventilator panel, a bracket having a part occupying a position in said slot and being of a length approximating the length of the slot, an attaching flange extending laterally outwardly from the lower end of said part and secured to the base of the channel-shaped bottom bar, a latch arm pivoted to said part, and means on the main frame engageable with the latch arm in one position thereof to secure the ventilator in its closed position relative to the main frame.

4. A ventilator window assembly comprising a main frame, a ventilator panel supported in the main frame for swinging movement about a generally vertically extending axis, a frame for the ventilator panel having an upwardly opening channel-shaped bottom bar for receiving the lower edge portion of the panel and having a slot in the inner flange of said bar spaced to one side of the axis of swinging movement of the ventilator panel, a bracket having an upstanding part occupying a position in said slot and being of a length corresponding substantially to the length of the slot, an attaching flange extending laterally outwardly from the bottom of said part into the channel of the bottom ventilator frame bar beneath the adjacent edge of the panel and secured to the base of said channel, a latch arm pivoted to the upstanding part and having a portion engageable with means on the fixed frame in one position of the arm to secure the ventilator in its closed position, and a finishing plate concealing said upstanding part and slot.
